UNITED STATES PATENT OFFICE.

WILLIAM F. VOSS, OF WILMINGTON, DELAWARE.

BOLSTER.

SPECIFICATION forming part of Letters Patent No. 643,572, dated February 13, 1900.

Application filed September 1, 1899. Serial No. 729,176. (No model.)

To all whom it may concern:

Be it known that I, WILLIAM F. VOSS, a citizen of the United States, residing at Wilmington, in the county of New Castle and State of Delaware, have invented certain new and useful Improvements in Bolsters, of which the following is a specification.

My invention relates to bolsters, and in particular to those types which are adapted for use in connection with car-trucks and car-bodies, the object being the production of an improved structure which will not appreciably deflect when subjected to severe strains in service and allow the side bearings to come in contact each with the other, which shall consist of few parts and be comparatively light in weight, which will have the mass of material composing the same properly distributed, which will involve a minimum amount of labor in its formation, and which, withal, shall constitute a superior device for better performing the functions demanded of ordinary bolsters.

With the above main object in view my invention consists, objectively, in a metallic bolster having a longitudinal opening or openings and the metal above and below the opening or openings and at the ends integral and a king-post.

It further consists in a bolster composed of two flanged beams, each beam having its web split and the flanges spread apart and said bolster provided with a king-post.

It still further consists in a bolster composed of parallel flanged beams suitably united, each beam having an opening at the center and provided with a king-post and of greater depth at the center than at the ends.

Finally, it consists in certain novelties of construction and arrangements and combinations of parts hereinafter set forth and claimed.

The accompanying drawings illustrate three pictured examples of the physical embodiment of the invention constructed and arranged according to the best modes or methods I have so far devised for the practical application of the principle.

Figure 1 shows one form of my bolster as adapted for use with a car-truck. Fig. 2 is a sectional view of Fig. 1. Fig. 3 illustrates a form of the bolster adapted for use as a car-

body bolster. Fig. 4 is a perpendicular cross-sectional view of Fig. 3, taken at the center. Fig. 5 is a perpendicular cross-sectional view 55 of a bolster in which the main elements consist of channel-beams.

Referring to the several figures, the letter A designates the ordinary diamond frame of a car-truck.

B is the bolster as a whole.

C are I-beams, which constitute the main elements of the bolster.

D are openings in the I-beams, each opening made by splitting the web of an I-beam a suitable distance each side of the center and stretching a flange or flanges.

E are king-posts, in this instance consisting of metal plates riveted to the webs of the beams adjacent the flanges, as shown.

F is a metallic plate riveted to the top flanges of both beams.

G is a metallic plate riveted to the bottom flanges of the beams.

H is one of the bolster-guide castings riveted to the web of an I-beam.

I is a brake-hanger carrier made integral with the guide-casting, and J is a center plate.

It will be observed that the two forms of the bolster shown specifically in Figs. 1, 2, 3, and 4 are respectively adapted for use with a car-truck and as a body-bolster for cars. The former has both flanges of each I-beam bent on a curve during the process of stretching to make the openings D D, whereas in the latter 85 form the lower flanges of the beams only are stretched, the upper ones retaining their straight horizontal shapes, so as to fit the bottom of the car-body.

In Fig. 5 the letters K K designate channel-beams, which may be used in lieu of I-beams when so desired. I have shown these channel-beams located in parallel perpendicular planes some distance apart. They may, however, be so located that the webs will be in 95 frictional contact or a short distance apart, when a single king-post only may be employed for both beams.

I prefer to use in the construction of my bolster commercial rolled or fashioned iron or 100 steel beams—such, for instance, as shown—in which the webs are of substantially uniform thickness and the flanges of uniform dimensions, inasmuch as such beams can be

obtained in open market at a low price as compared with beams which are of a complex or irregular form.

From the foregoing it will be seen that I

- 5 have produced a bolster which fulfills all the conditions set forth as the purpose or object of my invention. In each form shown the greatest depth is at the center, where the weight of the load is supported, the beams 10 are integral at the ends, the webs are in parallel perpendicular planes, and the mass of metal properly distributed in a manner proportionate to the strains to which it is or may be subjected.
- 15 While I have specifically illustrated and described only three pictured forms of the objective physical embodiment of my invention, I do not thereby intend to limit its scope to such examples, inasmuch as the same can be 20 embodied in other forms and shapes. Modifications in construction may likewise be introduced. For the I-beams or channel-beams may be substituted Z or other shaped beams. The beams may be united by other means 25 than the identical top and bottom metallic plates F and G and king-posts of a different shape from those illustrated may be used. These and many other changes may be introduced at the discretion of the manufacturer without constituting a substantial departure.

What I claim as new, and desire to secure by Letters Patent, is—

- 30 1. A composite bolster made of beams having webs of substantially uniform thickness arranged in parallel perpendicular planes and flanges of uniform dimensions; said bolster having a central opening, and being provided with means for uniting the beams, and 35 a king-post.
- 40 2. A bolster comprising two flanged beams having their webs split and the flanges sepa-

rated to form openings; means for uniting the beams; and a king-post; the webs of the said beams being of substantially uniform 45 thickness.

3. A bolster comprising two flanged beams having their webs split and the lower flanges bent to form openings; means for uniting the beams; and a king-post; the webs of the 50 beams being of substantially uniform thickness.

4. A bolster comprising two flanged beams having their webs split and flanges separated; top and bottom plates which unite the beams; 55 and a king-post.

5. A composite metallic bolster comprising two flanged beams having central openings, 60 D D; king-posts, E E; a top plate; and a bottom plate.

6. A metallic bolster comprising two channel-beams provided with webs of substantially uniform thickness located in parallel perpendicular planes, and having a central opening; means for uniting the beams; and 65 a king-post.

7. A metallic bolster made of rolled flanged beams having their webs of substantially uniform thickness and flanges of uniform dimensions; means for uniting the beams; and a 70 king-post; the said beams having their webs split intermediate the ends so as to preserve each beam integral, and having their flanges separated to form openings, so that the greatest depth of the bolster will be at the center 75 and gradually diminish in depth toward the ends.

In testimony whereof I affix my signature in presence of two witnesses.

WILLIAM F. VOSS.
